(57) **CLAIM**

The ornamental design for a boat mooring apparatus, as shown and described.

DESCRIPTION

FIG. 1 is a top view of a boat mooring apparatus according to the invention.

FIG. 2 is a side right view of the left side view, being a mirror image thereof.

FIG. 3 is a front view thereof.

FIG. 4 is a bottom view thereof.

FIG. 5 is a rear view thereof.

FIG. 6 is a top view of a second embodiment of the boat mooring apparatus.

FIG. 7 is an enlarged isometric partial section clearly showing the details of the connection taken at 7 of FIG. 1. FIG. 8 is an enlarged isometric view clearly showing the connection taken at 8 of FIG. 1.

FIG. 9 is an enlarged isometric view clearly showing the connection taken at 9 of FIG. 1.

FIG. 10 is an enlarged isometric view clearly showing the connection taken at 10 of FIG. 1; and,

FIG. 11 is an enlarged isometric view clearly showing the connection taken at 11 of FIG. 1.

The broken lines shown in FIGS. 2 and 7 are for illustrative purposes only and form no part of the claimed design.
